UNITED STATES PATENT OFFICE.

LINDA R. WADE, OF ST. LOUIS, MISSOURI.

DESIGN FOR A BUST-PAD.

SPECIFICATION forming part of Design No. 35,666, dated February 4, 1902.

Application filed November 7, 1901. Serial No. 81,514. Term of patent 7 years.

To all whom it may concern:

Be it known that I, LINDA R. WADE, a citizen of the United States, residing at St. Louis, State of Missouri, have invented and produced a new and original Design for Bust-Pads, of which the following is a full, clear, and exact description, reference being had to the accompanying drawings, forming a part hereof.

Figure 1 is a plan of the pad. Fig. 2 is a top edge view thereof, and Fig. 3 is a perspective view of the pad.

As shown in the drawings, the leading and material features of my design consist of two convexo-concave pad-sections P, the upper adjacent edges of said sections being curved outwardly, the maximum curvature being adjacent or contiguous to the reentrant angle A formed by said curved edges. The adjacent reduced ends of the pad-sections are connected by a narrow neck N, whose lower edge is concave, the base of the concavity being located opposite the angle A. Said concave

curvature gradually assumes a convexity along the lower edge of the pad-section, eventually approaching the upper gradually concave edge of such pad-section until the two edges virtually narrow to a reduced width or end B.

As seen from the drawings, the upper edge of each pad-section is in the form of a reverse curve, whereas the lower edge is a convex curve up to the point of the central concavity at the base of the neck N.

Having described my invention, what I claim as new, and desire to secure by Letters Patent, is—

The design for a bust-pad, as herein shown and described.

In testimony whereof I affix my signature in presence of two witnesses.

LINDA R. WADE.
